PAGE 3

FIG. 5

FIG. 6

FIG. 7

FIG. 8

FIG. 1 is a front perspective view of a portable phonograph embodying my new design with the top cover in a closed position;

FIG. 2 is a front perspective view of the phonograph with the top cover in an open position;

FIG. 3 is an enlarged plan view of the portable phonograph as seen in FIG. 2;

FIG. 4 is an enlarged side elevational view looking from the right side of FIG. 1, the opposite side being substantially a mirror image thereof;

FIG. 5 is an enlarged side elevational view looking from the right side of FIG. 2;

FIG. 6 is an enlarged bottom view;

FIG. 7 is an enlarged rear elevational view of the portable phonograph as seen in FIG. 1; and

FIG. 8 is an enlarged rear elevational view of the portable phonograph as seen in FIG. 2.

I claim:

The ornamental design for a portable phonograph or the like, substantially as shown and described.

The dominant feature of my invention resides in the portion of the phonograph shown in full lines, as characterized by a pillow recessed in and removable from the lid of the housing, substantially as shown.
